UNITED STATES PATENT OFFICE.

CHARLES DENNISTON BURNEY, OF KILMESTON, ALRESFORD, ENGLAND.

AERONAUTICAL APPARATUS.

1,073,567.

Specification of Letters Patent. Patented Sept. 16, 1913.

Application filed December 14, 1912. Serial No. 736,936.

To all whom it may concern:

Be it known that I, CHARLES DENNISTON BURNEY, a subject of the King of Great Britain and Ireland, residing at Dean 5 Holme, Kilmeston, Alresford, in the county of Hants, England, have invented new and useful Improvements in and in Connection with Aeronautical Apparatus, of which the following is a specification.

10 This invention relates to aeronautical apparatus and in particular to aeronautical machines intended to ascend from or alight upon water and has for its object to increase the efficiency and enhance the safety of such 15 machines; a further object being to obviate the necessity for employing supporting bodies of the "float" or "punt" type which are liable to injury with consequent loss of buoyancy of the apparatus as a whole.

20 In the accompanying drawings, Figure 1 is a side elevation illustrating a hydro-aeronautical apparatus constructed according to my invention; Fig. 2 being a corresponding front elevation.

25 When applying my invention, by way of example, to an apparatus of the heavier-than-air type, furnished with laterally extending planes or "wings" for affording support during flight, I construct the 30 fuselage of the apparatus as a water-tight boat-like structure A; and beneath the same, I arrange hydropeds B whereon are mounted suitably disposed hydroplanes b; the latter being arranged in step formation, that is 35 to say, in different horizontal planes.

The hydropeds B are arranged obliquely with a considerable outward "rake," as shown in Fig. 2, with the effect that the lifting force produced by the hydroplanes b carried by either of the hydropeds is communicated directly to the nacels or body portion of the apparatus through the hydroped concerned. Additional rigidity is imparted to the hydropeds by connecting them 45 by means of a cross-tie b'. Under-ties E connected to the hydropeds B at comparatively low points serve to insure the rigidity of the hydroped structure.

At a suitable point toward the tail of the 50 apparatus, a vertical hydroped D furnished with hydroplanes d is also provided for use in imparting "lift" to that portion of the apparatus.

Adjacent to the lowermost hydroplanes b,

I arrange one or more propellers C, adapted 5 for use in water and capable of being driven from the main engine of the apparatus. As the latter, under the influence of these propellers or of the aerial propeller or propellers F, or of both, gathers speed, "lift" is 60 imparted to it by degrees; and finally, its whole weight becomes transferred from the hydroplanes to the aeroplanes as the machine is launched in flight.

By the construction above described, a favorable 65 metacentric condition is attained and the stability of the apparatus when floating at rest or traveling at a low speed is considerably improved.

Before alighting upon water, the water- 70 propellers C are set in motion, with the effect that the lower portion of the apparatus is maintained well in advance and the risk of piqué is obviated.

I claim:—

1. A hydro-aeronautical machine, comprising a water-tight boat-like body, dependent and laterally diverging hydropeds directly affixed to said body and carrying water-propellers, and hydroplanes 80 mounted on said hydropeds.

2. A hydro-aeronautical machine, comprising a water-tight boat-like body, dependent and laterally diverging hydropeds directly 85 affixed to said body and connected by cross-ties, hydroplanes carried by said hydropeds, a propeller for working in air, and water-propellers arranged in conjunction with hydroplanes to convert a portion of the longitudinal thrust exerted by said water propellers into "lift" exerted upon the apparatus. 90

3. A hydro-aeronautical machine, comprising a water-tight boat-like body, dependent and laterally diverging hydropeds directly 95 affixed to said body and connected by cross-ties, hydroplanes carried by said hydropeds, a propeller for working in air, and water-propellers mounted upon said hydropeds and arranged in conjunction with hydroplanes to convert a portion of the longitudinal thrust exerted by said water-propellers into "lift" exerted upon the apparatus. 100

4. In a hydro-aeronautical machine, a body, dependent hydropeds on said body, hydroplanes on said hydropeds, said hydropeds diverging from their point of attachment to the body, and a cross-tie between 105 said hydropeds producing a triangular

2
structure wherein the hydropeds afford each other mutual support.

5. In a hydro-aeronautical machine, a body, aerial supporting surfaces attached to said body, dependent hydropeds attached to said body and diverging from their point of attachment, hydroplanes on said hydropeds,

a cross-tie connecting said hydropeds, and under-ties connected to the hydropeds at comparatively low points.

CHARLES DENNISTON BURNLEY.
